UNITED STATES PATENT OFFICE.

JOHN A. SWORBELL, OF JERSEY CITY, NEW JERSEY, ASSIGNOR TO HYMAN BRESLAVSKY, OF NEW YORK, N. Y.

DESIGN FOR A RING.

Application filed May 2, 1923. Serial No. 6,025. Term of patent $3\frac{1}{2}$ years.

To all whom it may concern:

Be it known that I, JOHN A. SWORBELL, a citizen of the United States, and a resident of Jersey City, in the county of Hudson and State of New Jersey, have invented a new, original, and ornamental Design for Ring, of which the following is a specification, reference being had to the accompanying drawing, forming part thereof.

Figure 1 is a plan view of a ring, showing my new design.

Figure 2 is a side elevation of the ring shown in Figure 1.

I claim:

The ornamental design for a ring, as shown.

JOHN A. SWORBELL.
